UNITED STATES PATENT OFFICE

2,100,600

BACK-BAND BUCKLE

Charles Smallwood, Washington, N. C.

Application June 24, 1937, Serial No. 150,168

3 Claims. (Cl. 24—189)

This invention relates to back-band buckles of the type shown, for example, in Patent 770,397 issued to me on September 20, 1904.

It has been found in practice that buckles constructed as disclosed in the patent mentioned, are objectionable because of the excessive wear on the band resulting from the angular edges presented thereto which tend to cut into and sever the band so as to render it useless after a comparatively short period of use. The buckle has also been objectionable because of its weakness at the point where the chain-hook is located.

An object of the present invention is to provide a buckle which eliminates angular or sharp wearing portions contacted by the band and, instead, only subjects the band to pressure from a smooth rounded surface where it extends from the clamp to the end of the buckle.

A further object is to provide the buckle with a bearing rib rounded as stated and which also acts as a reinforcement to resist buckling or bending of the device when subjected to excessive strain.

A further object is to so position the chain-hook as to render it more durable and less likely to break off than where constructed and arranged as heretofore.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing—

Figure 1 is a plan view of a buckle embodying the present improvements.

Figure 2 is a section on line 2—2, Figure 1.

Figure 3 is a section on line 3—3, Figure 1.

Referring to the figures by characters of reference 1 designates a base plate one end of which is gradually tapered along curved lines to the base of a hook 2 which overlies the plate, the amount of material located at each side of the hook being such as to resist any tendency of the hook to bend relative to the base or to break off when subjected to excessive strain.

Transverse slots 3 and 4 are formed in the base for receiving a band B. The slot 4 nearest hook 2 is formed by removing metal bodily from

the base. Slot 3, which is adjacent to and parallel with the opposite edge of the base, is produced by slitting the base to form a lip 5 which is folded back onto the base so as to present a rounded surface 6 constituting that wall of slot 3 nearest the adjacent edge of the plate or base. This wall 6 thus constitutes a bearing for the band B which, because of its smooth rounded formation, will not bite into and wear or abrade the band. This will be apparent by referring to Figure 2. The opposite wall of slot 3 is also rounded, as indicated at 7 so that excessive wear will not occur at that point.

Adjacent to the sides of the base 1 of the buckle at points between the ends of the slots 3 and 4, are located ears 8 which are struck up from the base and formed with openings 9. Between these ears there is provided an abutment shoulder 10 formed by pressing a rib 11 upwardly from base 1, this rib having a rounded ridge 12. The rib 11 not only presents a rounded bearing to the band B engaging the buckle, but also serves to stiffen the buckle so as to resist bending of the base when the buckle is subjected to excessive strain.

Journalled in the apertures 9 are studs 13 extending from the ends of a flange 14 provided at one end of a clamping plate 15 from which extends a tongue 16. This flange is so proportioned that, when a band B is inserted between it and the base 1, plate 15 can be rotated on the axis of the studs 13 so as to force the free longitudinal edge of flange 14 into contact with the exposed surface of the band B, thereby clamping the band against base 1 and also clamping it over the rounded ridge and against the shoulder of the rib 11. These positions of the parts have been illustrated in Figure 3 and it will be noted that when they are so located, the tongue 16, which has an offset end 17, bears against the plate or base 1 so as to limit the movement of the plate in one direction.

Flange 14 can be formed with teeth or serrations 18 as shown in Figures 2 and 3 if so desired and, if these serrations are employed, corresponding ribs and grooves can be pressed into base 1 as indicated at 19 for the purpose of receiving those portions of the band thrust against the base by the teeth or serrations 18. It is to be understood, however, that under certain conditions it is not necessary to use teeth or serrations 18 and the corresponding grooves 19. Instead the flange 14 can be formed with a straight gripping edge and that portion of the base cooperating therewith can be made flat.

In practice the clamping plate 15 is swung at right angles to the position shown in the drawing so as to swing its flange 14 toward hook 2 and away from shoulder 10 and base 1. The band B is then inserted forwardly through slot 3, over the rib 11, between plate 1 and flange 14, and then back through slot 4. Thereafter plate 15 is swung about its axis so as to move flange 14 toward shoulder 10. This action will result in clamping the band between flange 14 and the base 1 and also binding it against shoulder 10 and ridge 12 of the rib 11. As the contacted walls of slot 3 are rounded, it will be apparent that the pulling action exerted by the band B will not produce excessive wear on the band from these walls of the slot 3 and as the bearing ridge 12 of the rib 11 is also rounded, there will be no undesirable wear on the band at that point. Consequently a band used with a buckle such as herein described will last much longer than where buckles such as shown in my patent referred to are employed.

It will be noted by referring to Figure 3 that the inturned portions 17 of the tongue 16 is supported close to the end of the hook 2 when the plate 15 is in clamping position. Thus this inturned portion 17 constitutes a guard for preventing an engaged object, such as a chain, from slipping off of the hook 2.

The rounded wall of slot 3 is effected by bending the metal in the formation of the slot and, if desired, this bend can be to any angle less than the 180° angle shown in Figure 3.

What is claimed is:

1. A buckle including a base, a clamping plate 35 mounted for swinging movement thereon and having a clamping flange cooperating with the base, there being band receiving slots in the base, and a stiffening rib between the slots and coop-

erating with the flange of the clamping plate to frictionally hold a band inserted through the slots and across the rib, said rib having a substantially perpendicular abutment shoulder cooperating with the flange and merging into a rounded bearing ridge. 5

2. A buckle including a base having parallel band receiving slots, there being a lip folded back onto the base, said lip being located along one side of one of the slots and forming a rounded wall 10 for said slot, a stiffening rib upstanding from the base between and parallel with the slots and having a substantially perpendicular abutment shoulder merging into a rounded ridge for engagement with the band, a clamping plate fulcrumed on the base and having a flange for cooperation with the shoulder to bind a band on the base and against the shoulder, and means on this clamping plate and cooperating with the base for limiting the movement of the clamping plate. 15 20

3. A buckle including a base having parallel slots, ears extending from the base between the ends of the slots, one of said slots having a lip constituting a rounded wall of the slot and folded back on the base, said slots constituting means 25 for receiving a band overlying that portion of the base between the ears and between the slots, a stiffening rib struck from the base between the ears and parallel with the slots, said rib having a substantially perpendicular abutment shoulder 30 merging into a rounded ridge constituting a bearing for the band, and a clamping plate fulcrumed in and extending between the ears, said clamping plate having a flange cooperating with the base to bind upon the adjacent portion of the band and 35 grip said band against the shoulder, said plate having a tongue inturned against the base.

CHARLES SMALLWOOD.
